UNITED STATES PATENT OFFICE.

WADE ROBINSON, OF NEW YORK, N. Y.

PEN-CLEANER.

SPECIFICATION forming part of Letters Patent No. 620,674, dated March 7, 1899.

Application filed July 18, 1898. Serial No. 636,225. (No model.)

To all whom it may concern:

Be it known that I, WADE ROBINSON, a citizen of the United States, residing at No. 12 East One Hundred and Thirty-first street, in the city of New York, county and State of New York, have invented a new and useful Pen-Cleaner, of which the following is a specification.

My invention relates to improvements in that class of pen-cleaners in which a sponge or absorbent cloth or fabric is retained in a cup or bowl partly filled with water or other fluid; and the object of my invention is to provide for the purpose of cleaning a pen a means which shall be simple, cleanly, neat in appearance, and at all times serviceable. I attain this object by the means described herein, and illustrated in the accompanying drawings, in which—

Figure 1 is a perspective view of the pen-cleaner with cover open, and Fig. 2 is a sectional view of same with cover closed.

Similar letters refer to similar parts in each figure.

The pen-cleaner is provided with a cup *a*, constructed of glass, hard rubber, or any other suitable material, having the annular groove *b*, into which is fitted immovably the annular ring *c*, constructed of metal, hard rubber, or any other suitable material and provided on the upper half of its outer circumference with the screw-thread *d*, an annular collar *f*, constructed of metal, hard rubber, or any other suitable material, provided on the inner side of its perpendicular extension with a screw-thread *h*, adapted to screw down on the screw-thread *d* of the annular ring *c*, a cover *k*, constructed of metal, hard rubber, or any other suitable material in hollow hemispherical form and attached to the annular collar *f* by means of an ordinary hinge *l*, and with a cleaning device having a convex resilient surface protruding through and above the annular collar *f* and means to support it in that position and across which run ridges or corrugations. The conventional form of this device illustrated in the accompanying drawings is constructed of a resilient sphere *p*, preferably a hollow soft-rubber ball of a diameter slightly larger than the inside diameter of the horizontal extension of the annular collar *f* and resting on the pedestal *m*, constructed of glass, hard rubber, or any other suitable material in tubular form, open at both ends, the ends being spread outward, the lower end slightly more than the upper. The pedestal *m* is of a height sufficient to cause the sphere *p* to protrude through and above the annular collar *f* a distance slightly less than half its diameter. The sphere *p* is provided with a removable hood or cover *s*, constructed of any suitable absorbent skin or fabric, in which are stitched or fastened in any suitable manner three such folds or plaits as will form the ridges or corrugations *o o o*. The hood or cover *s* is placed over the sphere *p* in such a manner that the ridges or corrugations *o o o* are brought evenly on top and that its lower part hangs down and is submerged in the water or fluid indicated by the horizontal dotted lines and contained in the cup *a*, substantially as illustrated in Fig. 2. Thus it will be seen that the hood or cover *s* by reason of its capillary attraction is kept constantly moist throughout. The ridges or corrugations *o o o* on the hood or cover *s* are of a size, distance apart at the center, and converge at a point consistent with utility, substantially as illustrated in the drawings.

The several parts of the cleaning device are maintained in the positions as described and illustrated by means of the annular collar *f*, which is screwed down on the annular ring *c* by means of the screw-threads *d* and *h*. The hood or cover *s* is made capable of removal from the sphere *p* in order that when it has become worn out it may be replaced by another of similar construction.

The cover *k* is provided to protect the surface of the cleaning device when not in use. The construction of the cleaning device described above and illustrated in the drawings is substantially as shown; but its form may be varied, its requisites being a convex resilient surface across which run ridges or corrugations and means to support it.

To clean a pen by means of my pen-cleaner, the convex or upper side of the pen is drawn or rubbed across the surface of the cleaning device and the concave or under side of the pen is drawn or rubbed along one of the ridges *o o o* of the cleaning device, exerting at the same time a slight downward pressure, thus

causing the surface of the cleaning device by reason of the depression in it so made to conform to the convex and concave shapes of the upper and under sides of the pen, and thus 5 accomplishing quickly and thoroughly the cleansing of the pen.

It will be seen that the pen-cleaner is equally well adapted to use as a moistener of stamps and envelopes and for other similar purposes.

10 What I claim is—

1. In a pen-cleaning device the combination with a receptacle for liquid, of a hollow resilient sphere, a support for said sphere located within the said receptacle, and adapted

15 to support the said sphere below the middle thereof, a hood of absorbent material covering the upper half of said sphere, the lower portion of said absorbent material arranged to hang down around the said support and be im-

mersed in the liquid contained in said receptacle substantially as specified.

2. In a pen-cleaning device the combination with a receptacle for liquid of a resilient surface suitably supported so that it shall be above the level of the liquid in said receptacle, and an absorbent hood or covering for said resilient surface, provided with ridges or corrugations, corresponding substantially in cross-section with the cross-section of a pen to be cleaned, the lower portion of said hood or covering arranged to hang down and be immersed in the liquid contained in said receptacle, substantially as specified.

WADE ROBINSON.
